UNITED STATES PATENT OFFICE.

PAUL R. SLEDGE, JR., OF AUGUSTA, GEORGIA.

ARTICLE-SUPPORT.

1,181,040.

Specification of Letters Patent. Patented Apr. 25, 1916.

Application filed May 24, 1915. Serial No. 30,121.

To all whom it may concern:

Be it known that I, PAUL R. SLEDGE, Jr., a citizen of the United States, residing at Augusta, in the county of Richmond and State of Georgia, have invented new and useful Improvements in Article-Supports, of which the following is a specification.

This invention relates to means for supporting articles, such as trays, canopies, mosquito bars, curtains, etc., from iron, brass and other metallic beds.

One object of the invention is to provide an article support comprising parts which may be firmly attached to and supported from the bed against liability of displacement, or disconnection from shocks or vibrations.

A further object of the invention is to provide an article support which may be applied without injury to the bed and the attaching posts of which may be arranged in different positions according to the character of the article to be supported or to the bed structure.

The invention consists of the features of construction, combination and arrangement of parts herein fully described and claimed, reference being had to the accompanying drawings in which:—

Figure 1 is a side elevation showing the application of the invention to a bed. Fig. 2 is a top plan view of the same. Fig. 3 is a vertical transverse section on line 3—3 of Fig. 1. Figs. 4 and 5 are perspective views of the corner brackets. Fig. 6 is a view of one of the saddle brackets. Fig. 7 is a view of a clamping or seat block used in connection therewith. Figs. 8 and 9 are views showing different applications of the parts shown in Figs. 6 and 7. Fig. 10 is a sectional view showing the use of the saddle bracket in conjunction with a modified form of block. Fig. 11 is a view of a modified form of saddle bracket. Fig. 12 is a view of a supporting bracket.

In carrying my invention into practice, I provide means attachable to the side rails 1 of an iron, brass or other metallic bedstead 2, for the purpose of supporting any desired article therefrom, such as trays, canopies, costumes, racks and various other articles, in such a manner as to hold the same clear of the floor, and without marring or injuring the bedstead, or in any manner interfering with it being moved about from

place to place while the article or articles are supported thereon. The supporting means may be employed for domestic purposes or for the use of dealers in displaying articles in a way to economize floor space. 60

The supporting means includes a saddle bracket or casting 3, comprising a rectangular or oblong rectangular block, recessed to form a receiving slot 4 and arms or lugs 5 and 6 at the opposite sides thereof. These 65 arms or lugs may be coextensive in thickness and other dimensions, or substantially so, and extending through the body of the bracket and the said lugs 5 and 6 are slots or openings 7 and 8 intersected at the ends 70 of the block by longitudinal openings 9 each receiving a winged clamping screw 10. Formed in the body of the plate, on opposite sides of the transverse center thereof, are openings 11, for a purpose hereinafter 75 described.

The block 3 is adapted for use in connection with a clamping or seat block 12, which is of a form corresponding to the saddle bracket and the opening 4 therein and to fit 80 snugly within said opening. Two of the adjacent sides of this block are cut away to provide intersecting recesses 13, providing an L-shaped seat to receive one of the rails 1, which is designed to be clamped between said 85 seat and adjacent sides or walls of the recess 4. The block 12 is designed to be held in position by a bolt 14 passing through one of the openings 11 and provided with a retaining nut 15.

It will be seen from the above that the saddle bracket may be applied to any of the ordinary angle metal rails of a bedstead, Fig. 8 showing the bracket applied horizontally to an ordinary form of angle 95 metal rail having a vertical web and a horizontal web, the latter extending inwardly from the upper edge of the vertical web. When the bracket is so applied standards or uprights, or other elements to be supported may be fitted within the slots 7 and 8 and secured by means of the set screws 10. Fig. 9 shows the bracket and block applied in a vertical position, thus disposing the slots 7 and 8 to horizontally receive parts 100 to be supported or suitable reinforcing means. The described construction of the block and saddle bracket adapts the bracket to be secured horizontally or vertically upon the top or bottom of the rail 1 or upon either 110

side of said rail, and to rails in which the horizontal web extends inwardly from the lower edge of the vertical web instead of inwardly from the upper edge thereof. The 5 openings 11 adapt the bracket for interchangeability of application in the manner described, as well as to right or left side rails, as will be readily understood.

In some cases the saddle bracket may be 10 modified in construction, as shown in Fig. 11, wherein the saddle bracket 3^a is provided with but a single slot 7 which extends through the body thereof and the lug 5^a, the other lug 6^a being reduced in thickness, 15 and but one of the set screws 10 being employed. This construction of saddle bracket may be employed whenever and wherever it is unnecessary to have more than one receiving slot and clamping screw although 20 this modified form of bracket is otherwise adapted to perform all of the functions of the bracket 3 and to be applied interchangeably in the same manner. In some 25 types of metallic beds, the side rails are of tubular form, as shown at 1^a in Fig. 10, and for use in conjunction with this type of rail I provide a block 12^a having a concavity or recess 13^a of suitable size and form to receive and engage the rail tube, which 30 block may be employed in conjunction with either of the saddle brackets 3 or 3^a.

For the purpose of connecting and reinforcing two or more of the brackets 3 or 3^a when applied to either the side, head or 35 foot rails of a bed, I provide bracing brackets or members 16 and 17. The member 16 is adapted for use as a corner brace to prevent relative movement of right angularly 40 related rails of a bedstead and consequent play or vibration of the elements and articles supported. This bracket consists of an upright body portion 18 formed with a receiving slot 19 to receive an upright or article to be supported and having a threaded opening 20 intersecting said slot and provided with a set screw 21 to engage and hold the upright. Extending from said body portion 18 in opposite directions and substantially at right angles to each other 45 are arms 22 having lateral portions 23 at their ends terminating in depending shanks 24 to engage the slots 7 or 8 of brackets 3 or 3^a and to be engaged by the set screws 10 cooperating with the aforesaid slots, 50 whereby the brace will not only be firmly supported but will connect and rigidly tie and brace two saddle brackets, such as two of the brackets 3 or 3^a secured to one of the side rails and a head or a foot rail of 55 a bedstead. By this means both saddle brackets will be rigidly tied and connected, as well as the rails of the bedstead mentioned, while the brace itself will be firmly fastened in position, thus preventing movement of 60 the parts of the bed or of the supported 65

articles, and obviating the shaking or vibration of the articles, as is common with prior devices. It will be understood, of course, that the brackets when so connected will be held with the rails against relative motion, 70 and the standards or uprights, or article supported by the brackets, will also be rigidly held, thus preventing objectionable oscillation or vibration of supported elements in moving the bed from place to place or 75 as a result of floor vibrations. Furthermore, it will be evident that the article or articles may be supported wholly above the floor of the room for use or display, and without marring or injuring the bedstead, 80 or preventing it from being moved from place to place as desired.

The bracket 17 consists, like the bracket 16, of a body portion 25 having a receiving slot 26, threaded opening 27 and set screw 85 28, and also having oppositely extending arms 29 and 30. These arms, however, project in opposite directions from the body portion in alinement with each other, and the arm 29 terminates in a shank 31 to engage one of the bracket saddles 3 or 3^a, while the arm 30 terminates in a forked portion 32. This form of brace 17, which like the brace 16 is also a corner brace, is adapted particularly for use where the bedstead is 90 without a head rail or foot rail, as sometimes is the case in bedsteads of very cheap construction, the fork 32 being arranged to engage an adjacent corner post of the bedstead by which the parts will be firmly connected and braced. The two types of corner braces 16 and 17 may be employed on either 95 the inside, outside, head or foot of the bedstead and be disposed either in a normal position in which it is fitted into the brackets 100 from above, or in an inverted position in which it will be fitted into the brackets from below, the construction being such that absolute rigidity will be retained and the supporting and bracing members rendered capable of being arranged to suit different or 105 varying conditions of service. Where two of the brackets 3 are vertically disposed at either side or upon opposite sides of a bed, supporting bracket members 33 may be 110 fitted in the upper slots and secured by the cooperating set screws 10, while a transverse reinforcing bar 34 fits in the lower slots and is secured by the other set screws 115 10. The supporting brackets 33 have sleeves 120 or sockets 35 to receive standards or uprights 36 adapted to be fastened in the position by set screws 37, allowing articles of various kinds to be supported while the supporting means and bedstead are held rigid 125 against disconnection or relative vibration, even when the bed is moved from place to place, the advantages of which will be apparent. The structures described also permit the articles to be supported above the 130

floor line, so as to prevent the same from becoming soiled.

I claim:

1. In an article support for attachment to bedsteads, the combination with slotted bracket members adapted for engagement with portions of a bedstead at right angles to each other, of a reinforcing bracket member having arms arranged at right angles to each other and provided with portions to engage the slots in said slotted bracket members, said reinforcing bracket member having means to receive and support an element or article to be supported.
- 15 2. In an article support for attachment to bedsteads, the combination with U-shaped

saddle brackets adapted for engagement with portions of a bedstead at right angles to each other, of a reinforcing bracket member having arms arranged at right angles to each other and having laterally extending and depending portions to engage said saddle brackets, said reinforcing bracket member having means to receive and support an element or article to be supported. 20 25

In testimony whereof I affix my signature in presence of two witnesses.

PAUL R. SLEDGE, JR.
